FILLING STOP MOTION FOR LOOMS

William H. Bell, Greenwood, S. C.

Application February 6, 1957, Serial No. 638,564

2 Claims. (Cl. 139—374)

The present invention relates to looms and more particularly to improvements in the filling stop mechanism of a loom.

Modern day looms operate at high speed and the loom parts are subject to much vibration. Satisfactory operation of the so-called center fork stop mechanism of looms depends upon proper alignment of an arm or extension of the knock-off plunger with the bunter carried by the loom lay. That is to say, when the center fork tines detect the absence of the filling in the shed on any given pick, and a linkage is set into motion for positioning the bunter so that it will engage the arm of the knock-off plunger to stop the loom, it is essential that this arm of the knock-off plunger be precisely positioned for engagement by the bunter, otherwise the bunter may miss it and the loom will fail to stop. If the loom is not stopped on the first pick of a broken filling, there will be missed picks in the cloth which will not be discovered until the work reaches the cloth room.

In most present day looms, the operating connection between the knock-off lever and plunger is such that there is no substantial downward force upon the head of the knock-off plunger to hold it in firm engagement with the breast beam extension, and consequently when the loom vibrates during operation, the head of the knock-off plunger is frequently elevated slightly or tilted with respect to the breast beam and the contact arm of the knock-off plunger is misaligned with respect to the bunter so that the latter cannot properly engage it to stop the loom.

that the latter cannot properly engage it to stop the loom. The connection between the knock-off lever and the knock-off plunger, which is the essence of the present invention, eliminates this difficulty entirely and the head of the knock-off plunger is constantly held firmly, yet slidably, upon the flat breast beam extension and prevented from being elevated from the breast beam or tilted, due to vibration, so that the arm of the knock-off plunger is always accurately aligned with the bunter when the bunter is in position to engage it.

It is the primary object of this invention to provide means for assuring that the knock-off plunger arm will be held in the proper position during the operation of a high speed loom for proper engagement by the bunter to stop the loom instantly when required.

A further and more specific object is to provide an improved connection between the knock-off lever and knock-off plunger of a loom filling stop mechanism, whereby vibration of the loom will not elevate or move the knock-off plunger arm from proper alignment with the bunter.

A further object is to provide a novel adjustable element or bushing carried by and reacting against the relatively rigid knock-off lever and holding the head of the knock-off plunger in contacting or sliding engagement with the flat breast beam extension beneath it.

A further object of the invention is to provide a novel and improved connection between the knock-off lever and knock-off plunger for the above-stated purposes.

2

which connection is readily adaptable to existing looms, with substantially no alteration of the same, and also adaptable to new looms, with highly improved results in both cases.

5 Other objects and advantages of the invention will be apparent during the course of the following description.

In the accompanying drawings, forming a part of this application and in which like numerals are employed to designate like parts throughout the same,

10. Figure 1 is a fragmentary perspective view of a loom stop motion or mechanism embodying the invention.

Figure 2 is an enlarged fragmentary vertical section taken substantially on line 2-2 of Figure 1.

Figure 3 is a fragmentary plan view of the improved connection between the knock-off lever and plunger of Figures 1 and 2.

Figures 1 and 2. In the 1st and 2nd years of the experiment, the following

In the drawings, wherein for the purpose of illustration is shown a preferred embodiment of the invention, reference is made first to Figure 1, wherein the numeral 10 designates a fragmentary portion of the well-known bunter carried by the loom lay 11. The bunter 10 is movable by a conventional linkage, not shown, in response to the detecting by the center fork tines of the absence of the filling in the shed on any pick, so that the bunter which travels with the lay will be aligned with a knock-off plunger arm, to be described, and will engage the same to immediately stop the loom. The control or operation of the bunter 10 is conventional and well-known, and need not be described or shown in detail in the present application. United States Patent 1,865,930 to Lindsjo discloses a typical control or operating means for the bunter carried by the lay of the loom, and the identical bunter operating means may be suitably employed in connection with the bunter 10 of the present application.

35 In Figure 1, the numeral 12 designates the loom breast beam, which has an integral flat horizontal extension 13 or table. The usual knock-off plunger 14 is mounted above the breast beam extension 13 and has a forward

generally rectangular head 15 adapted to rest upon and contact the flat extension 13. The head 15 preferably has a flat bottom face to assure proper seating upon the breast beam extension 13. A fixed guide bracket 16 is preferably formed integral with the breast beam extension 13 and receives and supports knock-off plunger in a well-known manner for horizontal longitudinal movement in response to contact by the bunter 10. At its trailing end, the knock-off plunger 14 has secured thereto a lateral extension or arm 17, preferably provided with a notch 18 to be engaged by the bunter 10 when the latter is positioned upon the lay so as to stop the loom.

90 The construction thus far described is all conventional and well-known and it should be unnecessary to go into further detail with respect to these elements.

A horizontally swingable knock-off lever 19 is arranged above the breast beam extension 13 and pivoted thereto intermediate its ends as shown at 20. The end of the knock-off lever 19 remote from the plunger 14 is connected with the well-known shipper 21, as shown. The end portion 22 of the knock-off lever 19 adjacent the knock-off plunger is preferably upwardly offset somewhat so as to extend over the top of the rectangular head 15 in superposed relation therewith. The head 15 is provided at its top with an integral upstanding connecting pin element 23, which in conventional looms such as that shown in Patent 1,865,930, merely engages rather loosely through an opening or slot formed in the adjacent end portion of the pivoted knock-off lever. It is because of this conventional construction that loom vibration causes the knock-off plunger head 15 to elevate slightly or tilt upon the breast beam extension 13, with the resulting misalignment of the arm 17 with respect to the bunter 10.

In the present improved construction, the knock-off

lever portion 22 has a screw-threaded opening 24 formed therethrough adjacent the element 23, and an adjustable screw-threaded bushing or element 25 has screw-threaded engagement within the opening 24 and is bodily mounted upon the lever portion 22, above the head 15. As shown in the drawings, the bushing 25 is provided in its lower end with a central cylindrical opening 26, adapted to snugly pivotally receive the pin extension 23 of knock-off plunger head 15. The depth of the opening 26 is preferably substantially equal to the height of the pin extension 23 above the top face of the head 15, Figure 2. The lower end of the bushing 25 is adapted, when the bushing is adjusted downwardly, to engage the top face of the head 15 at substantially the same time that the top of the pin extension 23 would engage the top wall of the opening 26. The screw-threaded bushing 25 has a lock nut 27 mounted thereon above the lever portion 22, as shown, for the purpose of securely locking the bushing 25 with respect to the lever 19 after adjustment of the bushing. The desired pivotal connection between the knock-off lever 19 and knock-off plunger 14 is afforded by the engagement of the pin extension 23 within the opening 26 of the adjustable bushing 25.

When the bushing 25 is turned or adjusted downwardly, by means of a screw driver or the like, its lower end may be brought into light engagement with the top flat face of the head 15, and the bushing 25 cannot move upwardly from the head 15 since it will react against the knock-off lever 19 which is quite rigid and firm upon its pivot. Consequently, the bushing 25 will serve to hold down the head 15, substantially in contact with the flat breast beam extension 13 at all times. As the loom vibrates during rapid operation, the head 15 will not be elevated from the extension 13 or tilted relative thereto, and the arm 17 will therefore be held in perfect alignment with the bunter 10, when the latter is positioned to engage the knock-off plunger arm 17 for stopping the loom. In other words, the adjustable bushing 25 and associated elements is capable of exerting exactly the desired degree of downward pressure upon the knock-off plunger head 15 to hold the same firmly against the flat extension 13 of the breast beam, while at the same time permitting the head 15 to slide freely upon the extension 13 should the knock-off plunger 14 move in response to engagement of the bunter 10 with the arm 17.

Except for the above improved operating connection between the knock-off lever 19 and knock-off plunger 14 and the resulting improved alignment of the arm 17 with the bunter 10, the general mode of operation and construction of the center fork stop motion is conventional and well-known, and need not be described further in the present application.

Should the knock-off plunger 14 be moved forwardly by the bunter 10, the shipper 21 will be detached from its holding notch and the loom will be instantly stopped, as is well-known. As stated above, the general construction and mode of operation is shown in Patent 1,865,930 to Lindsjo. The essence of the present invention resides in the improved connection between the knock-off lever 19 and plunger 14, together with the overcoming of loom vibration, which has previously adversely affected the loom stop mechanism. The invention greatly improves the effectiveness of the entire filling stop motion or mechanism.

In this connection, it is believed that the use of the means constituting the subject matter of this invention will result directly in a substantial saving of time, labor

and money in the mill, due to the obvious fact that the proper weaving of the cloth, free of defects, depends to a large degree upon an effective and fool-proof filling stop motion.

5 In connection with the present invention, it should be understood that the reciprocating knock-off plunger 14 has sufficient lateral play or clearance in the guide bracket 16 to permit normal operation of the knock-off lever 19 without any binding at the pivot pin 20 or pin element 23. 10 It is to be understood that the form of the invention herewith shown and described is to be taken as a preferred example of the same and that various changes in the shape, size and arrangement of parts may be resorted to, without departing from the spirit of the invention or the scope of the subjoined claims.

Having thus described my invention, I claim:

1. A loom stop mechanism comprising in combination a substantially flat breast beam extension, a knock-off lever pivoted to the breast beam extension and swingable above the same, means actuated by said lever for stopping the loom when the lever is swung in one direction, a reciprocatory knock-off plunger mounted adjacent the top of the breast beam extension and adapted to be actuated by the bunter of the loom and including 20 a head portion underlying the knock-off lever and disposed between the knock-off lever and said breast beam extension, the knock-off lever having a screw-threaded opening formed therethrough adjacent said head, a screw-threaded element having screw-threaded engagement within said opening and being adjustable toward and from said head of the knock-off plunger and having a recess in its lower end, a projection carried by the top of said head and engaging within said recess for forming a pivotal connection between the knock-off plunger and lever, said 30 screw-threaded element adapted to exert a desired downward pressure upon said head to hold the same substantially in sliding contact with the top of the breast beam extension, and means for holding said screw-threaded element in a selected adjusted position.

2. In a loom filling stop mechanism, a breast beam extension having an upper flat face, a reciprocatory knock-off plunger to be aligned with a lay carried bunter and mounted upon the breast beam extension, a head carried by the knock-off plunger and having a flat bottom face 40 for substantial sliding contact with the flat upper face of the breast beam extension, an upstanding pivot element carried by said head, a knock-off lever pivotally mounted upon the breast beam extension and swingable above said extension and having an end portion overlying 45 said head, said end portion of the knock-off lever having a screw-threaded opening formed therethrough larger than the pivot element of the head, a bushing having screw-threaded engagement within the screw-threaded opening of the knock-off lever and having an opening in its lower end pivotally receiving the pivot element, said bushing being adjustable toward and from said head and adapted to urge the head into substantial sliding contact with the breast beam extension and being unyielding against the upward thrust of said head during the operation of said mechanism, and a lock nut having screw-threaded engagement with said bushing at the upper side of the knock-off lever.
